ELECTROMECHANICAL TRANSLATING DEVICE

Application filed April 18, 1928. Serial No. 270,861.

This invention relates to an electro-mechanical translating device and more particularly to such a translating device adapted to operate at sound frequencies, and is particularly applicable to phonograph pick-ups, sound speakers, microphones and the like.

It is an object of this invention to provide a device of the class described, which shall be simple, rugged and economical in construction, reliable in operation, and compact, without, however, requiring extremely precise workmanship in construction.

It is a further object of this invention to provide a device of the class described, in which the customary armature of magnetic material and its accompanying fine wire coil is eliminated.

It is still a further object of this invention to provide a device of the class described, in which the distortions, due to saturation of an armature of magnetic material, are eliminated.

The features of novelty which I believe to be characteristic of my invention are set forth 25 with particularity in the appended claims. My invention itself, however, both as to its fundamental principles and as to its particular application will best be understood by reference to the specification and accompanying drawing, in which:

Figure 1 is a view in side elevation of a phonograph pick-up according to my invention, and showing, diagrammatically, an amplifier and loud-speaker associated with the 35 pick-up.

Figure 2 is a front elevation view of the phonograph pick-up of Figure 1.

Figure 3 is a detail sectional view on an enlarged scale, taken on lines 3—3 of Figure 1.

Figure 4 is a diagrammatic view showing the operation of my invention, and also showing the invention adapted for use as a microphone or sound-speaker.

In apparatus of the class described, as generally constructed, there is provided a magnet, a winding for the electric currents to be utilized or generated, and an armature of magnetic material, usually of iron, arranged for vibration in the field of the magnet in such manner as to provide a change of flux

with respect to the conductors of the coil. The coil is customarily in the form of a winding embodying a large number of turns of fine wire, the resistance and impedance of which are relatively high.

In the operation of such a device a certain amount of distortion is introduced by hysteresis losses in the armature. Furthermore the law of operation of such a device shows that there is a tendency to set up additional 60 electrical variations of double the frequency of the mechanical vibrations. Moreover, since the wire used in the coil is very fine, there is great danger of open circuits or short circuits in the windings.

In accordance with my invention, I eliminate these difficulties by providing a non-magnetic conductor including a loop having a portion mounted for movement in a magnetic field of fixed value, such portion of the 70 conductor being arranged to move through a field which is substantially constant within the limits of movement, whereby the output of the device is very free from distortion. The said portion of the conductor is preferably 75 in the form of a U disposed in the air gap substantially parallel to the pole faces of the magnet. The upper open ends of the U are flexibly mounted in such a manner as to permit them to move toward and away 80 from each other when the base of the U is moved in a direction approximately parallel to the arms of the U. Such movement, as will be understood, causes a change in the number of lines of magnetic flux enclosed by the U, 85 and the loop of which it is a part, and thereby causes the generation of an electro-motive force which is linearly proportional to the rate of change of flux enclosed by the moving portion of the conductor, as long as the flux 90 density of the field in which the said portion of the conductor moves is constant.

Referring now more particularly to Figure 1, in which I have shown my invention as applied to a phonograph pick-up, 1 designates the energizing magnet having pole pieces 2 and 3 defining an air gap, within which the movable portion of the non-magnetic conductor acted upon by the magnetic flux is vibrated. The said movable portion of 100

the conductor is preferably in the form of a single relatively heavy wire or ribbon bent in the form of a U and having arms 4 and 5. The upper ends of the arms 4 and 5 are carried on terminal contacts 6 and 7 respectively, which are clamped between an internal support 10 mounted within the magnet 1, and cover pieces 8 and 9, and held firmly in position by means of screws 11 and 12 engaging the support block 10. The downwardly extending portions of the terminals 6 and 7 are preferably tapered and bent inwardly as shown at 6^a and 7^a to increase their flexibility and engage the upper ends of the arms 4 and 15 5 of the U, where a suitable low resistance connection is established, as for example, by soldering. The upper ends of the terminals 6 and 7 are preferably bent outwardly and twisted as at 6^b and 7^b to provide for connections with suitable leads. The lower end of the U is secured to one end of a stylus bar or link 13 carrying at its opposite end a suitable stylus point 15 adapted to engage a record 16, to be vibrated thereby as the 25 record is revolved by the turntable 17. The stylus bar or link 13 is arranged to be pivoted at a point intermediate its ends as for example by the provision of wings or projections 14 thereon, mounted between supporting plates or arms 19 and 20 secured to opposite sides of the magnet 1. The stylus bar 13 may be pivotally held in position in the arms 19 and 20 by means of a pin 14^a passing through the supports 19 and 20 and 30 through the wings 14 and the stylus bar 13. The pick-up may be carried and supported between the arms 18^a and 18^b of a support 21, which in turn is inserted in a hollow tube 25, and the support 21 may be secured in position 40 in the tube in any suitable manner, as for example by means of pin 22 passing through the tube 25 and the support 21.

The tube 25 is pivotally mounted at its opposite end on a forked member 26, which, in turn, is rotatably mounted in a suitable supporting sleeve 27, to provide for movement of the pick-up in following the record groove.

In the case of a vertical cut record for which the pick-up shown is primarily adapted, suitable feed mechanism may be provided for advancing the pick-up as the turntable is rotated. Since such mechanism forms per se no part of the present invention, and since any known mechanism may be used for the purpose, it is not shown.

The leads 28 and 29 which are connected to the terminals 6^b and 7^b may be passed into the tubular support 25 through suitable openings therein and carried out to the desired point. Any suitable arrangement of amplifier 40 may be used, if desired; after amplification, the currents may be passed into a suitable loud speaker 41. Since the resistance and impedance of the pick-up itself are very

low, a very high step-up transformer should be interposed between the pick-up and the amplifier, in case the usual form of thermionic vacuum tube amplifier is utilized. In the arrangement shown, the leads 28 and 29 may be connected to the primary winding 30 of a suitable transformer comprising a core 31 of magnetic material and a secondary winding 32, which is connected to the input circuit of the amplifier 40. To obtain the best results, the resistance and impedance of the primary winding 30 should be kept relatively low in order to match that of the pick-up, while the characteristics of the secondary winding 32 should be made to match those of the amplifier 40.

I have obtained very satisfactory results with the construction shown when the primary winding 30 consists of only a few turns of heavy copper ribbon, while the secondary winding 32 is in the form customary for audio frequency windings operating in the input circuit of the usual vacuum tube amplifier.

Referring now more particularly to Figure 4, I have shown diagrammatically the method of operation of the movable portion of the conductor disposed in the magnetic field according to my invention. In this figure, the normal or static position of the said movable portion or U of the conductor is shown in the full lines while the dotted lines show the position of the same after movement away from the normal position. Assuming that the stylus point 15 is moved in an upward direction by the rotation of the record 16, the opposite end of the lever 13 will be moved downwardly, thereby tending to move the lower end of the U down: this, in turn, will pull the lower ends of the wings 6^a and 7^a down and cause them to bend outwardly, as shown in dotted lines in Figure 4, in which the movement taking place is exaggerated for the purpose of illustration. This, in turn, causes an outward bending or deformation of the upper ends of the arms 4 and 5, thereby changing the cross sectional area of the magnetic flux enclosed by the U and by the loop of which the U is a part. Since the arms 4 and 5 move in opposite directions, and are connected in series by the connection at the bottom of the U, the voltage generated in the said arms will be in phase and will add to produce a voltage equal to twice that generated in each arm.

It is to be noted particularly, that by making the pole pieces 2 and 3 sufficiently wide so that the magnetic field density within the limits of movement of the moving U is essentially constant, the voltage generated will be very closely proportional to the speed of movement of the arms of the U transversely in the field, as a result of which the voltage generated is particularly free from distortion of the type which occurs with the usual form of vibrating armature, in which the reluc-

tance of the magnetic circuit varies with the position of the armature.

It will be understood that the principles of my invention may be applied in other forms of apparatus, such for example as loud speakers and microphones. For example, in Figure 4, I have shown a suitable diaphragm 38, such as a cone, secured to one end of a driving rod 35, as for example by means of nuts 36, the other end of the driving rod being secured to a link or member 13' which is rigidly connected to the closed end of the U disposed between the pole pieces of the magnet 1. In the operation of my device as a loud speaker, the telephone currents for actuating the speaker are supplied to the terminals 6 and 7, and thence to the movable U, the movement of which is substantially the same regardless of whether the apparatus is employed as a motor or as a generator. The apparatus shown in Figure 4 may thus be utilized either as a loud speaker or as a microphone. In case it is desired to operate the apparatus as a microphone, the sounds to be picked up are allowed to impinge against the diaphragm 38, thereby producing movement of the movable U, and in turn causing the generation of currents corresponding to the sounds to be picked up.

While I have shown a phonograph pick-up particularly adapted for operation with vertical cut records, it will be understood that such a pick-up may be readily adapted to lateral cut records, by mounting the stylus arm so that the stylus point vibrates laterally instead of vertically, and by mounting the pick-up in a horizontal position.

While I have shown and described certain preferred embodiments of my invention, it will be understood that modifications and changes may be made without departing from the spirit and scope of my invention, as will be understood by those skilled in the art.

I claim:

1. An electro-mechanical translating device comprising in combination a magnet having an air gap, a non-magnetic conductor including a portion in the form of a U mounted in said air gap and having the open ends of said U yieldably supported for movement at an angle to the arms of said U, and a vibratile member secured to the closed end of said U.

2. A phonograph pick-up comprising in combination a magnet having an air gap, a non-magnetic conductor in the form of a U mounted in said air gap, means for yieldably supporting the open ends of said conductor for movement at an angle to the arms of said U, a stylus arranged to be vibrated by a record, and a connection between said stylus and the closed end of said conductor.

3. An electro-mechanical translating device comprising in combination a magnet having an air gap, a non-magnetic conductor including an open-ended loop portion disposed

in said air gap and having the open ends of said loop portion yieldably supported for movement at an angle to the sides or arms of such loop portion, and a vibratile member secured to the closed end of said loop portion.

4. A phonograph pick-up comprising in combination a magnet having an air gap, a non-magnetic conductor, including an open-ended loop portion disposed in said air gap, means for yieldably supporting the open ends of said loop portion for movement at an angle to the sides or arms of such loop portion, a stylus arranged to be vibrated by a record, and a connection between said stylus and the closed end of said loop portion.

This specification signed this 17th day of April 1928.
